LYNFORD A. WARD AND WILLIAM D. CHASE, OF BROOKLYN, NEW YORK.

IDENTIFICATION DEVICE FOR AUTOMOBILES.

1,153,278.

Specification of Letters Patent. Patented Sept. 14, 1915.

Application filed July 8, 1914. Serial No. 849,787.

To all whom it may concern:

Be it known that we, LYNFORD A. WARD and WILLIAM D. CHASE, citizens of the United States, residing at Brooklyn, in the county of Kings and State of New York, have invented new and useful Improvements in Identification Devices for Automobiles, of which the following is a specification.

The present invention relates to improvements in identification devices for automobiles and other vehicles, and the primary object of the invention is to provide a device of this character which will enable the proper authorities to determine with certainty the identity of the person to whom the automobile or vehicle number is issued, the device in its preferred form embodying a license or identification number having combined therewith an identification card which is sealed in such a manner that it cannot be removed or altered by unauthorized persons. One of the advantages of an identification card of this character is that it prevents license numbers issued to one person for a particular automobile or vehicle from being used upon another automobile or by anyone other than the person to whom the license is issued, and it also enables the authorities to ascertain the identity of the person to whom the license is issued.

To these and other ends, the invention consists in certain improvements, and combinations and arrangements of parts, all as will be hereinafter more fully described, the novel features being pointed out particularly in the claim at the end of the specification.

In the accompanying drawing:—Figure 1 is a perspective view of an identification device for automobiles; Fig. 2 represents a horizontal section through the device, the seal being removed and the parts shown in separated position; Fig. 3 is a rear view of the device as shown in Fig. 1; Fig. 4 is a detail view of the seal; Fig. 5 is a perspective view showing a somewhat modified form of device; and Fig. 6 is a perspective view of the rear portion of that member of the device shown in Fig. 5 which bears the number and the identification card.

Similar parts are designated by the same reference characters in the several views.

In that form of the invention shown in Figs. 1-4 inclusive, 1 designates the body or base or supporting member of the device

which is adapted to be appropriately attached or secured to the automobile or vehicle. In the present instance, the body of the device has an embossed portion 2 which bears a part of the serial identification number and data. The body of the device toward its opposite end is formed with a recess or pocket 3 containing an aperture 4. A transparent plate 5 is adapted to be seated in the recessed or pocket portion 3 to cover the aperture 4 and provide a transparent covering for a card or sheet 6 which latter is intended to be inscribed with a description of the person to whom the license is issued. A cover or member 7 is provided which is so related to the body of the device that it will seal the identification card in the pocket or space between the members 1 and 7 in a manner that will prevent its removal, destruction or alteration by unauthorized persons although it may be inspected readily by the proper authorities. In the construction shown, one end of the cover or member 7 has a tang 8 formed thereon which is adapted to be inserted endwise into a slot 9 formed in the body of the device, and the opposite end of the cover or member 7 has an apertured lug 10 adapted to register with a similar lug 11 on the body of the device, and by inserting the tang 8 into the slot 9, then bringing together the lugs 10 and 11 (the transparent plate 5 and inscribed card or sheet 6 being in position), and then applying a seal 12 to the lugs 10 and 11, the identification card or sheet is locked and sealed in the pocket between the base member 1 and the member 7 in such a manner that it is inaccessible without removal of the seal. However, the authorities can readily ascertain the identity of the person to whom the license is issued by viewing the identification card through the aperture 4 and transparent plate 5. The member 7 also bears part of the serial identification number for the vehicle.

In that form of the invention shown in Figs. 5 and 6, the device comprises a body or supporting or base member 13 which is adapted to be secured to the automobile or vehicle, and this body slidably receives a member 14 which bears the serial identification number of the automobile or vehicle on its outer side and is adapted to receive an identification card or sheet 15 on its inner side. Preferably the member 14 is hollowed, forming a pocket between it and the

member 13, to receive the identification card or sheet 15, as shown, and a device is provided to seal the identification card in the pocket between the members 13 and 14 5 and thus prevent unauthorized access to and removal of the identification card or sheet. In the construction shown, a pair of pins 16 project from the member 14, the identification card or sheet being impaled on these 10 pins, and a wire 17 is threaded through openings in the pins extending across the back of the identification card or sheet and a seal 18 is applied to the ends of the wire. Obviously the identification card or sheet is 15 then secured in position in a manner which will prevent access thereto or removal thereof by unauthorized persons. Apertured lugs 19 and 20 are also preferably provided on the members 13 and 14 respectively which 20 are adapted to register when the member 14 is slid into position, and a seal may be applied to these lugs to prevent unauthorized removal of the member 14 which, when 25 within the body 13, incloses the identification sheet or card.

An identification device of this character prevents the use of license numbers upon automobiles or vehicles other than the one

for whom they were issued, it enables the authorities to determine the identity of persons injured or killed in accidents, and it also enables the identity of persons who have abandoned the automobiles or vehicles. 30

What is claimed is:—

An identification device for automobiles 35 comprising a supporting or base member, a member coöperating therewith to form a pocket between it and the base member, an identification card contained in the said pocket, said second-mentioned member bearing a serial identification number separate from the identification means borne by the identification card and movable relatively to the base member to render said identification card accessible, together with means for 40 sealing the identification card in the pocket between the base member and the identification number bearing member. 45

In testimony whereof we have hereunto set our hands in presence of two subscribing 50 witnesses.
